WOOD HEEL TRIMMING MACHINE

Norris D. Dalton, Afton, Mo., and John F. Smith, Braintree, Mass., assignors, by mesne assignments, to Fred W. Mears Heel Company, Inc., Lawrence, Mass., a corporation of Massachusetts

Application September 24, 1956, Serial No. 611,644

5 Claims. (Cl. 144—154)

This invention pertains to a machine for trimming wood heel blanks preparatory to the final shaping of the heel. In this operation most of the excess material is removed from the sides of the heel blank so that the final shaping operation does not require so deep a cut.

An object of this invention is to provide a simple trimming mechanism which will be reliable in operation and easy to handle.

Another object is to provide such a mechanism which will be entirely automatic in operation except for feeding the blanks.

A further object is to provide improved clamping means for holding the blank during the trimming operation.

Further objects will appear from the following description taken with the accompanying drawings forming part thereof.

Generally stated, the apparatus comprises a rotary turret or disk member mounted on a horizontal shaft and providing a support for the heel blanks during the trimming operation. A plurality of heel-blank seats are spaced about the periphery of said support. Clamps, one for each seat, are mounted on the support and also a fluid-pressure unit for operating each clamp. A rotary valve of improved design is mounted on said shaft and connected to supply fluid pressure to each of said units during the travel of its heel-blank seat past the trimming cutters and to exhaust the same thereafter. The two trimming cutters are located so that the blank is moved past, and between them, so that each cutter operates on one side of the blank. These cutters are offset relatively to each other so that they operate on the blank successively. This provides that the clamp holding the blank must sustain the cutting force of only one cutter at a time. After the blank has passed the cutters its clamp is released and the blank dropped onto a chute for delivery to a suitable container.

A preferred embodiment of this invention is illustrated in the accompanying drawings, in which:

Fig. 1 is a perspective view, largely diagrammatic, of a mechanism embodying this invention,

Fig. 2 is a perspective view showing the relative positions of the rotary support and the cutters, and the way in which the blanks pass between the latter,

Fig. 3 is a plan view of the complete mechanism,

Fig. 4 is a section on line 4—4 of Fig. 3,

Fig. 5 is a section on line 5—5 of Fig. 3, and

Fig. 6 is an exploded view of the rotary valve controlling the clamps.

Referring to the drawings, 1 designates a suitable base on which the mechanism is mounted. A motor 2 is connected by a belt 3 to a speed-reducing gear box 4. The low-speed shaft 5 of this gear box carries a hub member 6. This hub member also receives an extension shaft 7 journaled at its other end in a bearing block 8.

Secured to the hub member 6 is a turret or disk member 9, which is thus mounted for rotation on the shaft 7 when driven by the motor 2. Mounted at suitable

2

intervals about the periphery of the disk 9 are heel-seat members 10 each provided with a side clamp jaw 11 and a rear stop 12. On the side of the disk 9 opposite to that of the jaw 11 is a clamp arm 13 pivoted on a bracket 14 secured to the disk 9 adjacent its center. The arm 13 has a jaw 15 positioned opposite the jaw 11. By placing the pivot bracket 14 near the center of the disk 9 the arm 13 becomes long enough to give the jaw 15 a substantially straight-line movement toward the jaw 11. A pin 16, slidably mounted in the disk 9 and biased by a compression spring 17, engages the arm 13 to move it outward, or to the right, Fig. 5, on its pivot.

Pivoted on a bracket 18 on the disk 9 adjacent the clamp arm 13 is a lever 19, one arm 20 of which carries a roller 21 engaging the arm 13 as shown in Fig. 5. The other arm 22 of the lever 19 is engageable by a pressure unit comprising a fluid-pressure cylinder 23 having movable therein a piston 24 operating a plunger 25 positioned to engage the arm 22. The cylinder 23 is mounted on the opposite side of the disk 9 to that on which the lever 19 is mounted, and its plunger passes through a suitable opening in said disk lined with a guide bushing 26. When fluid pressure is supplied to the cylinder 23 via a fitting 27, the piston 24 moves the plunger 25 to the right, Fig. 5, engaging the arm 22 to rock the lever 19 on its pivot. This causes the arm 20 to move the roller 21 to the left to move the clamp arm 13 against the pressure of the spring 17 to close the jaw 15 upon a heel blank on the seat 10.

As shown in Figs. 1 and 2, a pair of cutters 30 and 31, driven by motors 32 and 33 respectively, are positioned so that a heel-blank clamped on the seat 10 will be moved past said cutters between them, so that they operate on both sides of the blank to trim the same. Fig. 1 shows the mechanism in diagrammatic form with the disk 9 and its mounting moved somewhat to the left so that parts, otherwise hidden, may be seen. In this view also the clamps 13 have been simplified in construction and reduced in number in order to avoid crowding and confusion. In order to avoid imposing on these clamps the force required to hold the blank against the action of both cutters at the same time, one of the cutters is offset with respect to the other so that these cutters will engage the blank in succession rather than simultaneously. As shown in Fig. 4, the cutter 30 is elevated with respect to the cutter 31 to produce this offset.

The cutters 30 and 31 are mounted, respectively, on shafts 34 and 35 journaled in bearing blocks 36 and 37. The bearing block 37 and the motor 33 are mounted on a slide plate 38 movable in grooved guide rails 39 on the base 1. Similarly, the bearing block 36 and the motor 32 are mounted on a slide plate 40 movable in said rails 39. The block 36, however, is set upon spacer blocks 41 to provide the offset for the cutter 30 mentioned above. Each of the plates 38 and 40 is provided with a block 42 threaded to receive a screw 43 journaled in the base 1 and having a crank handle 44 for rotating the same. These screws provide means for moving the plates 38 and 40 along the ways 39 to adjust the spacing of the cutters. The plates may be clamped in adjusted position by clamp studs 45.

In order to operate the clamp arm 13 in timed relation to the rotation of the disk 9, the pressure units 23, 24, 25 are supplied by a rotary valve shown in Fig. 6. Mounted on the shaft 7 to rotate therewith is a valve plate 46 formed with a series of right-angle ducts 47 each extending from a port 48 in the outer cylindrical surface of the plate 46 to a port in the adjacent portion of the radial face 49 of said plate. Connected at each of said ports 48 is a fitting 50 which is connected by

a tube 51 with the fitting 27 of one of said pressure units (Fig. 5). A wear plate 52, of graphitic material, such as the material known by the trade name of "Graphitar," is loosely mounted on the hub portion of the plate 46 and keyed to said plate by a pair of pins 53 on the plate 46 which engage holes 54 in the wear plate. Said wear plate is formed with through holes 55 matching the ends of the ducts 47 in the face of the plate 46. A complementary valve plate 56 is slidably mounted on a bushing 57 surrounding the shaft 7 and supported in the bearing bracket 8. The plate 56 is keyed to the bracket 8 by pins 58 on said bracket entering matching holes (not shown) in the plate 56 to hold the latter stationary. Springs 59, engaging matching sockets in the bracket 8 and the plate 56, press said plate against the wear plate 52.

The face of the valve plate 56 which engages the wear plate 52 is formed with a circumferential groove 60 communicating with a duct 61 to which a fluid-pressure supply conduit 62 is connected. The groove 60 is aligned radially with the holes 55 and the ducts 47 of the rotating plate 46, and serves as an intake manifold to supply pressure to these ducts and their connected pressure units during a certain portion of each revolution of the disk 9. A similar groove 63, connecting with an exhaust port 64, provides an exhaust manifold for said units. Accordingly, as each of the ports 47, 55 comes opposite the groove 63 that unit will be exhausted and the clamp released.

In the operation of this device the disk 9 and the cutters rotate continuously and fluid pressure is continuously maintained in the supply conduit 62. The operator places heel blanks in the seats 10 as they pass, as indicated in Fig. 1. The groove 60 of the valve is so located that the blank is clamped near the top of its travel and the clamp maintained until just after the last cutter has operated on the blank. The cutters trim the opposite sides of the blank in succession as described above. Thereafter the exhaust manifold 63 operates to release the clamp and the trimmed blank is dropped into a chute 65 which conducts it to a suitable container. This sequence can be continued just as fast as an operator can load the seats 10 with blanks.

Various changes may be made in the details of construction, within the scope of the appended claims, without departing from the spirit of this invention. Parts of the invention may be used without the whole and improvements may be added while retaining some or all of the advantages of the invention.

We claim:

1. In a machine for trimming wood heels, the combination comprising, a rotary disk member providing a heel-blank support, a plurality of heel-blank seats peripherally arranged on said member and having clamp elements at one side of said member, a clamp arm for each of said seats pivoted on the other side of said disk member adjacent the center thereof and having a clamp element opposite said seat, spring means operating to move said arm away from said seat, a fluid-pressure unit on said disk member for each of said arms, and a lever pivoted on said member having one arm positioned for

engagement by said unit and another arm engaging said clamp arm to move the same into clamping engagement with a heel-blank in said seat.

2. A combination as defined in claim 1 in which said units are mounted on said first side of said members and have plungers extending through openings in said members to engage said levers.

3. In a wood-heel forming machine of the character described, a turret member mounted for rotation on a horizontal axis, a plurality of heel-seats peripherally arranged on the rim of said turret member, means for clamping a heel-blank in each of said seats, said clamping means including coacting clamp elements on opposite sides of the turret member holding the heel-blank so that it protrudes beyond the rim of the turret member, and cutter means positioned on opposite sides of the turret member to operate on opposite sides of said blanks as said turret member rotates.

4. In a wood-heel forming machine of the character described, a turret member mounted for rotation, a plurality of heel-seats peripherally arranged on the rim of said turret member, means for clamping a heel-blank in each of said seats, said clamping means including a clamp element disposed adjacent each seat at one side of the turret member, a coacting clamp element at the opposite side of the turret member, and means for opening and closing said clamp elements, the clamp elements holding the heel-blanks so as to protrude beyond the rim of the turret member, and cutter means positioned on opposite sides of the turret member to operate on opposite sides of said blanks as said turret member rotates.

5. In a machine for trimming wood heels, the combination comprising a rotary disc member providing a heel blank support, a plurality of heel blank seats peripherally arranged on the rim of said disc member, clamp elements for each seat at one side of said disc member, a coacting clamp arm for each of said seats pivoted on the other side of said disc member, resilient means operatively connected to said clamp arms tending to move said arms away from said seat, a fluid pressure unit on said disc member for each of said clamp arms, means interconnecting said fluid pressure units to said clamp arms to move the arms into clamping engagement with heel blanks in said seats, said clamp element and clamp arm on opposite sides of the disc member holding the heel blank so that it protrudes beyond the rim of the disc member, and cutter means positioned on opposite sides of the disc member to operate on opposite sides of said blanks as said disc member rotates.
